HYDRAULIC DOOR OPERATOR FOR
WAGONS

Joseph Kuchar, Chicago, Ill., assignor to Athey
Truss Wheel Co., Chicago, Ill., a corporation of
Illinois

Application April 23, 1934, Serial No. 721,877

12 Claims. (Cl. 298—35)

This invention relates to hydraulic door operators for wagons and trailers, and particularly to operators for doors on a wagon adapted to be operated by pressure liquid supplied from a preceding vehicle such as a tractor.

The invention is particularly adapted for use with wagons or trailers having bottom dump doors which open downwardly when released. In such wagons the load effects the opening of the doors when they are released and the door operator raises them to closing position after dumping.

One of the objects of the invention is to provide an improved hydraulic door operator.

15 A further object of the invention is to provide a hydraulic door operator which permits the doors to open freely under the action of the load when released.

20 A further object of the invention is to provide a hydraulic door operator with means for returning the hydraulic motor to its initial door closing or operating position while the doors are closed and before the load is dumped.

25 Other objects, advantages and capabilities of the invention will appear from the following description of preferred embodiments thereof, taken in conjunction with the accompanying drawings, in which

30 Figure 1 is an elevational view of a trailer embodying my invention, and a fragment of a tractor to which it is hitched;

Fig. 2 is a sectional view, on a considerably larger scale of the hydraulic cylinder employed in this embodiment of the invention;

35 Fig. 3 is a rear elevational view of the trailer showing the mechanism whereby the doors are closed;

40 Fig. 4 is a fragmentary sectional view taken on the line 4—4 of Fig. 3 showing part of the door control mechanism;

Fig. 5 is a similar view, the elements being in a different operating position;

Fig. 6 is a detail sectional view taken on the line 6—6 of Fig. 4;

45 Fig. 7 is an elevational view similar to Fig. 1 showing a further embodiment of the invention, and

Fig. 8 is a sectional view, similar to Fig. 2, of the hydraulic cylinder employed in this embodiment.

50 Referring to Figs. 1 to 6 of the drawings, the reference numeral 10 designates a wagon body supported on an arched axle 11, which in turn is supported at each end upon track laying wheels 12 of known construction. The bottom of the

hopper-like body 10 is normally closed by a pair of doors 13. These doors 13 are hingedly mounted at their outer edges upon the wagon and are adapted to meet on the center line of the wagon when they are closed. Each door 13 carries on its underside near its free edge a pair of pulleys 14, one pulley being located at the front end of the door, and the other at the rear end of the door. A cable 15 passes under the pulleys 14 and over a pulley 16 carried on the front of the wagon body. The ends of the cable 15 are secured to and wound upon a drum 17 rotatably mounted in bearing brackets 18, mounted on a channel 19 which is rigidly secured to the rear wall of the wagon body. It will readily be understood from Fig. 3 that when the drum 17 is wound up the tightening of the cable 15 closes the doors 13. The pulley 16 provides equalization between the effective lengths of the cable and ensures complete closing of both doors irrespective of variation in effective lengths of cable due to irregular building up of the wound cable on the drum 17 and other causes.

The shaft 20 of the drum 17 extends outwardly beyond one side of the wagon where it rigidly carries a small drum 21. The shaft 20 is supported in a suitable bearing 22 carried by the wagon adjacent the drum 21. The other end of the drum shaft projects to a lesser extent beyond the adjacent bearing bracket 18 and has keyed thereon a ratchet wheel 23. An operating handle 24 is provided for actuating the ratchet wheel 23 by hand. This handle has bifurcated ends 25 provided with elongated slots 26. These bifurcated ends are located on either side of the ratchet wheel 23 and the shaft of the drum 17 extends through the slots 26. The inner end of the bifurcated arms is connected by a tooth 27 which is adapted to engage the teeth of the ratchet wheel 23, and suitably manipulated by hand. Normally the handle 24 hangs downwardly and the tooth 27 is out of contact with the teeth of the ratchet wheel 23. To turn the drum 17 by means of the ratchet wheel 23, the handle 24 is raised to a horizontal position, the handle 45 is moved toward the ratchet wheel so as to cause the tooth 27 to engage the ratchet teeth. A downward force exerted on the handle 24 will cause rotation of the drum 17 in appropriate direction to close the doors 13.

50 A suitable pawl 28 is provided for maintaining the doors closed until it is desired to open them. This pawl and associated mechanism will herein-after be more fully described. The handle 24 provides a manual means for closing the doors 55

13, this manual means enabling the doors to be closed in the absence of a tractor or in the event of the power door operator breaking down.

- The pawl 28 is pivotally mounted in a frame 29. The frame 29 is pivotally mounted at 30 on the channel 19. The frame 29 is provided with a downwardly extending handle 31 whereby it may be swung upwardly, in counter-clockwise direction by the pivot 30, as viewed in Figs. 4 and 5. The result of such swinging is to elevate the pivotal support of the pawl 28 with the result that the weight of the doors and the load acting through the cable 15 on the drum 17, causes this drum and the ratchet wheel 23 to rotate carrying the ends of the pawl 28 with it into the position shown in Fig. 5. After the pawl 28 is moved to the position shown in this figure, the drum 17 is free to rotate to allow the doors to open to their full extent. The open doors are indicated in dotted lines on Fig. 3. The pawl 28 is balanced so that it is easily returned to its operating position by handle 31 or rope 41 and must be returned prior to winding up drum 17 by handle 24 or by power means which will hereinafter be described.
- The frame 29 is normally held in the position shown in Fig. 4 by means of a spring 32 which abuts against a pin 33 and against a washer 34 which abuts against nuts 35 threaded on the end of a rod 36. The rod 36 is pivoted at 37 to the channel 19 and the frame 29 is provided with an opening 38 which accommodates the spring 32, the rod 36 and, in the position of the parts illustrated in Fig. 5, the washer 34 and nuts 35. The rod 36 passes through an opening in the pin 33 and this pin projects laterally on each side into slots 39 formed in the frame 29 on each side of the opening 38.

It will be understood from the foregoing description that the pawl 28 may be elevated to release the load by suitable actuation of the handle 31. It is preferable to provide means whereby the frame 29 can also be elevated from a remote point, for example from the seat of the tractor 40 shown in the right-hand side of Fig. 1. Such means may comprise a rope 41 which extends from the tractor to the trailer, where it is attached to a lever 42. The lever 42 is rigidly carried on a shaft 43, which also carries rigidly a short arm 44 located at one side of the wagon, for example, the far side of the wagon, as viewed in Fig. 1. The arm 44 is connected by a rod or rope 45 which may suitably be guided in openings in the struts 46 on that side of the wagon. At the end of the wagon on which is mounted the drum 17, the rod or rope 45 is secured to an arm 47 rigidly mounted on a rod 48. The rod 48 is provided with a bearing in a bracket 49 mounted on the wagon, and the end remote from this bracket is supported on a bracket 50 carried by the channel 19.

Adjacent the bracket 50 the rod 48 has rigidly mounted thereon an arm 51 which is connected by a link 52 to the frame 29. It will readily be understood that when the rope 41 is pulled forwardly, the frame 29 is elevated, carrying with it the pawl 28, so that the drum 17 is released with the result that the load is dumped.

The drum 21 previously referred to has secured thereto a cable, chain or other suitable flexible member 53 which is adapted to be wound on the drum 21 when the drum 17 is rotated owing to the downward movement of the doors under the action of the load. The flexible member 53 is secured to the rear end of a piston rod 54. The piston rod 54 carries a piston 55 which is located

within a hydraulic cylinder 56 mounted on the adjacent side of the wagon body 10 and extending in the longitudinal direction thereof. The rearmost end of the cylinder 56 is connected by a flexible tube 57, pipes 58 on the wagon, and flexible hose 59 between the wagon and tractor 40, to a hydraulic pump 60 mounted on the tractor 40 and adapted to be actuated by the engine thereof. The pump 60 need not be described in detail since it may be any of a number of pumps known in the art. It is preferably substantially the same as the pump described and claimed in my co-pending application Serial No. 609,603 filed May 6, 1932 and issued Oct. 22, 1935 as Patent No. 2,018,269. This pump is controlled by a hand lever 61 which has five controlling positions, indicated *a*, *b*, *c*, *d*, and *e* on Fig. 1. In the position indicated in full lines in Fig. 1, that is position *a*, the pump 60 is unclutched from the engine and is not operating and free passage is provided for the return of fluid from the cylinder 56 to the hydraulic fluid reservoir 62.

In the position *b* of the hand lever 61, the pump 60 is clutched to the engine and the pump is still by-passed. When the hand lever 61 is moved to position *c*, pressure fluid is delivered to the hose 59, from whence it passes into the rear end of cylinder 56. The pawl 28 is returned to its operating position by handle 31 or by rope 41. By supplying pressure fluid to the rear end of the cylinder 56 the piston 55 is forced forwardly with the result that, if the doors are open, the flexible member 53 is drawn forwardly rotating the drum 21, and thereby the drum 17. The final result is that the doors 13 are closed and will remain closed until pawl 28 is again released for dumping the load or the contents of the body. The pump 60 is preferably provided with an automatic by-pass so that when the piston 55 is moved to its extreme position, the pump will automatically by-pass fluid thereby avoiding building up of extremely high pressure. When the hand lever 61 is returned to position *b* or *a*, the doors are left supported by the pawl 28 and the cylinder 56 is put into free communication with the reservoir 62.

As best shown in Fig. 2, the piston 55 carries a rearwardly extending open housing 64 which receives the forward end of a coil spring 65. The coil spring 65 engages a boss 66 on the front end of the cylinder. When pressure fluid is supplied to the rearward end of the cylinder 56, the piston 55 is moved to the right, as viewed in Fig. 2, and the spring 65 is compressed. The compressed spring 65 is located within the housing 64. It will be readily understood that when the hand lever 61 is returned to position *b* or *a* the spring 65 will expand, forcing the piston 55 rearwardly and displacing the fluid therefrom, which fluid is returned by the pipe connections previously mentioned, to the reservoir 62. The result of this return movement of the piston 55 by the spring 65 is that the flexible member 53 has slackened to the maximum extent and is left free for winding up upon the drum 21. Thus it will be understood that owing to the action of the spring 65, the doors 13 are free to open immediately the pawl 28 is released and are not impeded or slowed up by any dashpot effect which would be incurred if the rearward movement of the piston 55 were executed while the doors 13 were falling open. In other words, if the piston 55 had not previously been moved rearwardly, the opening of the doors 13 would move the piston 55 rearwardly and would displace the fluid in the cylinder 56 through the pipe connections to the 75

reservoir 62 while the doors were opening. The resistance of the fluid to rapid movement would create a dashpot or delaying effect which would impair the utility of the wagon with sticky loads, such as clay or certain other loads, such as frozen dirt. Such loads require, for efficient operation of automatically opening doors of this type, doors which are able to open immediately they are released.

10 The embodiment of the invention illustrated in Figs. 7 and 8 is substantially similar to that which has just been described. Consequently the same reference numerals are employed to indicate those parts which are identical in operation and function. The distinctive feature of this modification resides in the fact that no spring 65 is employed, but the piston is returned to initial position before the opening of the doors by pressure fluid provided by the pump 60. Owing to 20 the absence of the housing 64 and the spring 65, the cylinder 56 may be made substantially shorter. In addition to the pipe connections 51, 58, and 59 connecting the rear end of the cylinder 56 to one delivery outlet of the pump 60, I provide additional conduits 66, 67, and 68 connecting the forward end of the cylinder 55 to an outlet of the pump 60. When the actuating lever 61 is moved to position *c*, as shown in Fig. 7, pressure fluid is supplied to the rear end of the 30 cylinder 56 for the purpose of closing the doors 13 as before. When the actuating hand lever 61 is moved to position *d* the fluid is enclosed in the rear end of the cylinder 56, the piston 55 being located in the forward end of this cylinder. 35 When the actuating lever 61 is moved to the extreme position *e*, pressure fluid is supplied through conduits 68, 67, and 66 to the forward end of the cylinder 56 with the result that the piston 55 is moved to its extreme rear position in 40 the same manner as it was moved to this position by the spring 65 in the embodiment of the invention first described. The control lever 61 is now moved quickly to its initial position *a*, the pump 60 is rendered inoperative and the flexible 45 member 53 is elevated in slack condition so that the opening of the doors when they are released, occurs without any delay or dashpot effect owing to the employment of pressure fluid for closing the doors.

50 Although the invention has been disclosed in connection with the specific details of preferred embodiments thereof, it must be understood that such details are not intended to be limitative of the invention except in so far as set forth in the 55 accompanying claims.

Having thus described my invention, what I claim as new and desire to secure by Letters Patent of the United States is:

1. In a wagon, in combination, doors adapted to open and close, liquid operated means adapted to actuate the doors in one direction, said doors being operated in the opposite direction by gravity, actuating mechanism for moving said liquid operated means to its initial actuating position independent of movement of the doors, latch means for holding said doors against operation by gravity when the liquid operated means is in said initial position, and means to release said latch means.
2. In a wagon, in combination, doors adapted to open under the action of gravity, liquid operated means connected to said doors to close them, means operative independent of the door opening for actuating said liquid operated means into initial door-closing position, latch means for hold-

ing said doors closed when the liquid operated means is in said initial position, and means to release said latch means.

3. In a wagon, in combination, doors adapted to open under the action of gravity, a cylinder 5 on said wagon, a piston therein, means for supplying liquid under pressure to one end of said cylinder to cause said piston to close the doors, means independent of the door opening for moving said piston towards said end of said cylinder 10 after the doors are closed, latch means for holding the doors closed when said piston is thus moved, and means to release said latch means.

4. In a wagon, in combination, bottom doors adapted to be opened by their weight and the 15 weight of the load, a liquid operated cylinder on said wagon, a piston therein, flexible means operatively connecting said piston to said doors, means for supplying liquid under pressure to one end of said cylinder to cause said piston to close 20 the doors, a spring for moving said piston back to its initial door-closing position when the pressure of the liquid is decreased, latch means for holding said doors closed when the piston is returned 25 to said initial position, and means to release said latch means.

5. In a wagon, in combination, bottom doors adapted to be opened by their weight and the weight of the load, a liquid operated cylinder on 30 said wagon, a piston therein, flexible means operatively connecting said piston to said doors, means for supplying liquid under pressure to one end of said cylinder to cause said piston to close the doors, a spring within the cylinder for moving said piston back to its initial door-closing position 35 when the pressure of the liquid is decreased, latch means for holding said doors closed when the piston is returned to said initial position, and means to release said latch means.

6. In a wagon, in combination, bottom doors 40 adapted to be opened by their weight and the weight of the load, a liquid operated cylinder on said wagon, a piston therein, flexible means operatively connecting said piston to said doors, latch- 45 ing means independent of the door closing mechanism for holding the doors closed, means independent of the door closing mechanism for unlatching said latching means, means for supplying liquid under pressure to one end of said cylinder to cause said piston to close the doors, and 50 means for supplying pressure fluid to the other end of the cylinder to move said piston back to its initial door-closing position, whereby the doors may fall open when unlatched without retarding dashpot effect of said pistons.

7. In a wagon, in combination, doors adapted to open and close, liquid-operated means adapted to actuate the doors in one direction, said doors being operated in the opposite direction by gravity, actuating means for moving said liquid-operated 60 means to its initial actuating position independent of movement of the doors, a valve adapted in one position to supply pressure liquid to said liquid-operated means and in another position to provide an outlet for the liquid thus 65 supplied, latch means for holding said doors against operation by gravity when the liquid operated means is in said initial position, and means to release said latch means.

8. In a wagon, in combination, doors adapted 70 to open under the action of gravity, liquid-operated means connected to said doors to close them, means operative independent of the door opening for actuating said liquid-operated means into initial door closing position, a valve adapted in 75

one position to supply pressure liquid to said liquid-operated means, and in another position to connect said liquid-operated means to a sump, latch means for holding said doors closed when the liquid operated means is in said initial position, and means to release said latch means.

9. In a wagon, in combination, doors adapted to open under the action of gravity, a cylinder on said wagon, a piston therein, a valve having one position for supplying liquid under pressure to one end of said cylinder to cause said piston to close the doors and in another position to connect said end of said cylinder to a reservoir, means independent of the door openings for moving said piston toward said end of said cylinder after the doors are closed and after the valve is moved to said second position, latch means for holding the doors closed when said piston is thus moved, and means to release said latch means.

10. In a wagon, in combination, bottom doors adapted to be opened by their weight and the weight of a load, a liquid-operated cylinder on said wagon, a piston therein, flexible means operatively connecting said piston to said doors, a valve having one position for supplying liquid under pressure to one end of said cylinder to cause said piston to close the doors and in another position to connect said end of said cylinder to a reservoir, a spring for moving said piston back to its initial door-closing position when the pressure of the liquid is decreased by moving the valve to said second position, latch means for holding the doors closed when the piston is in said initial position, and means to release said latch means.

11. In a wagon, in combination, bottom doors adapted to be opened by their weight and the weight of a load, a liquid-operated cylinder on said wagon, a piston therein, flexible means operatively connecting said piston to said doors, a valve having one position for supplying liquid under pressure to one end of said cylinder to cause said piston to close the doors and in another position to connect said end of said cylinder to a reservoir, a spring within the cylinder for moving said piston back to its initial door-closing position when the pressure of the liquid is decreased by moving the valve to said second position, a latch for holding the doors closed when the piston is in said initial position, and means to release said latch means.

12. In a wagon, in combination, bottom doors adapted to be opened by their weight and the weight of a load, a liquid-operated cylinder on said wagon, a piston therein, flexible means operatively connecting said piston to said doors, latching means independent of the door-closing mechanism for holding the doors closed, means independent of the door-closing mechanism for unlatching said latching means, a valve having one position for supplying liquid under pressure to one end of said cylinder to cause said piston to close the doors and in another position to connect said end of said cylinder to a reservoir, and means for supplying pressure fluid to the other end of the cylinder to move said piston back to its initial door-closing position, whereby the doors may fall open when unlatched without retarding dashpot effect of said piston.

JOSEPH KUCHAR.
